UNITED STATES PATENT OFFICE.

EARL C. JUSTICE, OF TULSA, OKLAHOMA.

SELF-OILING DIESTOCK.

Application filed September 23, 1925. Serial No. 58,145.

This invention relates to a die stock and one object of the invention is to so form the die stock that oil which is utilized to permit of threads being easily cut in a pipe may be carried in the handles of the die stock and fed to the portion of the pipe which is being threaded through a valve controlled conduit. This makes it unnecessary to use an oil can in order to apply the oil to the pipe. It has been found that when the oil is kept in an oil can and applied to the pipe which is being threaded most of the oil which is discharged from the can is wasted as too much is applied to the pipe and the surplus drips onto the floor. Waste is also caused due to the fact that the can will often fall onto the floor in an inverted position so that the oil drains out of it and very often the can will be lost by being dropped while traveling from one place to another or by being accidentally left when the pipe threader is moved from one place to another. By having the oil stored in the handles of the die stock which will hold more oil than an ordinary oil can, a large supply of oil may be kept ready for immediate use and this supply of oil economically used as only the amount necessary to properly lubricate the threads being cut will be discharged from the valve controlled conduit at one time.

This invention is illustrated in the accompanying drawing, wherein—

Figure 1 is a view showing the improved thread cutter in elevation with a portion of one of the handles and the socket into which it fits shown in longitudinal section;

Fig. 2 is a longitudinal sectional view taken on the line 2—2 of Fig. 1, and

Fig. 3 is a transverse sectional view taken on the line 3—3 of Fig. 1.

The die stock which is indicated in general by the numeral 1 is formed with the usual pipe passage 2 to receive the pipe which is to be threaded. A seat 3 is provided at the front of the die stock 1 and receives the dies 4 which are disposed at opposite sides of the pipe passage 2 and movable towards and away from each other so that they may be properly set to thread a pipe of a given diameter. At its ends the stock is formed with sockets 5 which are internally threaded and adapted to receive the handles 6, the handles consisting of lengths of pipe externally threaded at their inner ends so that they may be screwed into

the sockets 5 and having their outer end portions internally threaded to receive nipples 7 which project outwardly therefrom for engagement by removable caps 8. One of the caps 8 is provided with an air inlet port 9 beyond the outer end of the nipple engaged by this cap, and this nipple has the outer end portion of its bore 10 reduced to form a valve seat 11 for engagement by the valve plunger 12 slidably mounted in the nipple, so that oil may be prevented from leaking out of the handle when in a depending position. An abutment 13 is provided to prevent sliding of the valve plunger into the handle and is formed with an opening 14 so that air may pass into the handle. The other cap which is intended to be removed when it is necessary to fill the handles with oil which will flow from one handle to the other through the conduit 15 will be an imperforate cap and the nipple upon which this cap fits will have its axially extending bore or passage sufficiently large to permit the oil to be readily poured through the same into the handle. By having the cap shown at the left in Fig. 2 formed with the port 9 and inwardly opening check valve, air may enter the handle to prevent the formation of a vacuum therein, which would interfere with the application of oil to the pipe to be threaded, but when the handle is in an inverted position the valve prevents danger of the oil leaking outwardly through the port 9.

In the present illustration, the conduit 15 has been shown formed of separate pipe sections 16 connected at their adjacent ends by a T-coupling 17 and their outer ends secured by collars 18 to nipples 19 screwed into threaded openings 20 formed in the inner ends of the sockets 5. It will be understood, however, that the conduit may if so desired be cast integral with the die stock or secured thereto in any other practical manner. A branch 21 which is formed as an elbow enlarged intermediate its length to form a valve housing 22 has one end screwed into the T-coupling and its other end screwed into the enlarged internally threaded upper end portion of a part 23 which communicates with the pipe passage 2 between the dies 4. From an inspection of Fig. 3, it will be readily seen that, when the valve plug 24 is turned from the closed position shown to an open position, oil will be permitted to flow through the branch 21

of the conduit and directly onto the portion of the pipe being threaded. Therefore, the oil will not be wasted as the operator will only allow a sufficient amount to flow 5 through the port 23 to properly lubricate the pipe for easy cutting of the threads. After all of the oil in the handles has been used, it is merely necessary to remove the cap of the handle at the right in Figs. 10 and 2 and refill the handles.

Having thus described the invention, I claim:

1. In a die construction, a stock having its end portions formed with handle-receiving 15 sockets and its intermediate portion formed with a pipe-receiving passage and die seats to mount dies in operative relation to the pipe passage, hollow handles secured in said sockets and constituting oil reservoirs, an uninterrupted conduit connecting said sockets and intermediate its length provided with a branch pipe communicating with a passage 20 opening into said pipe passage between said die seats, a manually operated valve to control the flow of oil through the branch pipe of said conduit, and removable closures for the outer ends of said handles.

2. In a die construction, a stock having its end portions formed with handle-receiving 25 sockets, a conduit connecting said sockets and intermediate its length provided with a valve controlled branch opening into the pipe passage of said stock to deposit oil upon a pipe being threaded, and hollow handles secured in said sockets and provided with removable caps at their outer ends, one cap being formed with an air inlet 30 opening, and an inwardly opening check valve to control the passage of air through said opening.

3. In a die construction, a stock having its end portions formed with handle-receiving 35 sockets and its intermediate portion formed with a pipe-receiving passage and die seats to mount dies in operative relation to the pipe passage, handles secured in said sockets, one handle being hollow and constituting an oil reservoir, a conduit leading 40 from the socket carrying the hollow handle and communicating with a passage open-

ing into said pipe passage between said die seats, a valve for controlling the flow of oil into said pipe passage, an abutment disk in the outer end portion of said hollow handle and formed with an air passage, a closure cap having a head at its outer end and formed with an air passage adjacent its head, a nipple screwed into said cap and projecting therefrom and adapted to be screwed into the hollow handle to removably connect the cap with the handle, said nipple having a longitudinally extending bore formed with a reduced portion constituting a valve seat, and a valve plunger slidably longitudinally in the bore of said nipple into and out of sealing engagement with the valve seat and limited in its movement away from the valve seat by engagement with said abutment disk.

4. In a die construction, a stock having its 70 end portions formed with handle-receiving sockets and its intermediate portion formed with a pipe-receiving passage and seats to mount pipe-threading dies in operative relation to the pipe passage, a conduit connecting 75 said sockets and extending across said pipe passage, a valve controlled branch leading from said conduit intermediate its length and extending longitudinally of the pipe passage and communicating with a passage 80 opening into the pipe passage between the die seats to deliver oil upon the portion of a pipe being threaded, hollow handles secured in said sockets and constituting oil receptacles, removable caps for the outer ends 85 of said handles, one cap being provided with an air inlet opening, a nipple threaded into the last-mentioned cap and cooperating handle and having the outer end portion of its bore reduced to form a valve seat, a valve 90 plunger slidably in said bore for movement into and out of sealing engagement with the valve seat, and a disk in said handle inwardly of said nipple to limit movement of the plunger into the handle and formed with an 95 opening to permit passage of air into the handle when the valve plunger is out of sealing engagement with the valve seat.

In testimony whereof I affix my signature.
EARL C. JUSTICE. [L. S.]
